UNITED STATES PATENT OFFICE.

JOHN C. KLENK AND JOHN J. CRONIN, OF CHICAGO, ILLINOIS.

SUPPORTING DEVICE.

1,229,977.

Specification of Letters Patent. Patented June 12, 1917.

Application filed May 3, 1916. Serial No. 95,044.

To all whom it may concern:

Be it known that we, JOHN C. KLENK and JOHN J. CRONIN, citizens of the United States, and residents of the city of Chicago, county of Cook, and State of Illinois, have invented certain new and useful Improvements in Supporting Devices, of which the following is a specification.

Our invention relates to supporting devices, and more particularly to that class thereof generally known as gambrel sticks which are designed for use especially in the supporting of hogs in the course of dressing of the same in the travel of the hogs through packing plants.

The object of our invention is the production of a device of the character mentioned whereby a hog may be readily and expeditiously suspended in the position desired, and as easily and expeditiously released when desired.

A further object is the production of a supporting device which will in no way injure the parts with which the same comes in contact in the support of a hog, and further, one which will be of durable and economical construction.

With these objects in view, the invention consists in the combinations and arrangements of parts hereinafter described and claimed.

The invention will be best understood by reference to the accompanying drawings forming a part of this specification, and in which,

Figure 1 is a front elevation of a supporting device embodying the invention, and

Figs. 2 and 3 are enlarged sections taken on lines $x-x$ and $y-y$ respectively of Fig. 1.

The preferred form of construction, as illustrated in the drawings, comprises an elongated yoke or beam 1 adapted, in the employment of the device, to be suspended from a suitable carriage whereby the hog is moved along in the course of treatment to which the same is subjected. To prevent shifting of the yoke 1, relative to the carriage upon which the same is suspended, said yoke is provided, intermediate its ends, with downwardly opening recesses 1' for the reception of the portions of the carriage which engage with said yoke.

Provided at the respective ends of yoke 1 are bails 2 which are loosely connected with said yoke by means of links 3. Mount-

ed in each of said bails is a supporting member 4 mounted for swinging, about horizontal axes, upon trunnions constituted by screws 5 provided at the ends of the bail and projecting inwardly therefrom. The members 4 are substantially heart-shaped in form, said members being so balanced upon the trunnions 5, that the tapering ends of said members normally are positioned at the under sides of said members.

In use, the two hind feet of the hog, illustrated at A, are inserted into the members 4, the weight of the hog serving to carry the engaged portions of the feet downwardly into engagement with the converging sides of the members 4, which thus securely grip the same and lock the hog to the device.

To insure against slipping of the engaged portions from the members 4, the latter are formed at their inner sides with longitudinally extending ridges 6 V-shaped in cross section, as clearly shown in Fig. 3. These ridges, are, of course, adapted to engage firmly in the flesh of the inserted portions of the hog and thus preclude slipping. At the opposite or upper side of each member 4 is provided a forwardly projecting prong 7 which is adapted to engage with the rearward side of the inserted foot of the hog between the dew-claws of the same and thus prevent any relative rotary movement.

Release of the hog thus held in readily and expeditiously effected by simply tilting the members 4 to inverted position, since when this is done, it will be seen that, the engaged feet of the hog will slide into the larger portions of the members 4 and thus become automatically released. Inversion of the members 4, as mentioned, is effected by engagement with the lower ends of said members which are curved outwardly and downwardly, as shown at 8, for this purpose. Thus, with a construction, as set forth, it will be seen that a hog may be readily and quickly suspended in the position desired by simply inserting the hind feet of the hog into the members 4. This having been done, when the device is raised, the engaged feet of the hog will, by gravity, engage in the lowered tapering portions of the openings in the members 4 and the prongs 7 will engage with the rear sides of the engaged feet between the dew claws, resulting in the secure fastening of the hog to the supporting device, and without in any way cutting or bruising the flesh of the en-

gaged portions. When it is desired to release the hog, it is only necessary to engage the ends 8 of the members 4 and tilt the same upwardly, since when this is done, the 5 prongs 7 are moved to releasing position and the engaged hog feet slide by gravity from engagement with the converging gripping sides of the members 4, with the result that the hog automatically releases itself of its 10 own weight.

While we have illustrated and described the preferred form of construction for carrying out our invention, this is capable of variation and modification without departing 15 from the spirit of the invention. We, therefore, do not wish to be limited to the precise details of construction set forth, but desire to avail ourselves of such variations and modifications as come within the scope of the 20 appended claims.

Having described our invention what we claim as new and desire to secure by Letters Patent is:

1. A gambrel stick comprising a supporting member mounted for swinging on a horizontal axis positioned intermediate the ends of said member, said member having an opening therein for the reception of the object to be suspended, the lower portion of 25 said opening tapering downwardly for gripping the object inserted in said opening, substantially as described.

2. A gambrel stick comprising a supporting member mounted for swinging on a horizontal axis, said member having an opening 30

therein for the reception of the object to be suspended, the lower portion of said opening tapering downwardly for gripping the object inserted in said opening; and a prong provided at the opposite side of said member for engagement with the upper portion 40 of the object arranged in said opening, substantially as described.

3. A gambrel stick comprising a yoke; supporting members provided at the respective ends of said yoke and connected therewith for swinging about horizontal axes positioned intermediate the ends thereof, said members having openings therein adapted, when said members are in operative position, 45 to receive and grip inserted portions of the object suspended, substantially as described.

4. A gambrel stick comprising a yoke; bails depending from the respective ends of said yoke; and supporting members mounted in said bails for free swinging about horizontal axes intermediate the ends thereof, said members having openings therein adapted, when said members are in operative position, 50 to receive and grip inserted portions of the object to be suspended, substantially as described.

In testimony whereof we have signed our names to this specification in the presence of two subscribing witnesses.

JOHN C. KLENK.
JOHN J. CRONIN.
